Concrete and Asphalt Co., Maryville, Mo.

Filed Mar. 9, 1972, Ser. No. 233,405

Term of patent 14 years

Int. Cl. D25—03

U.S. Cl. D13—1 R

FIG. 1 is a top plan view of a portion of the roof thereof broken away to better illustrate the relief of the facade, and with the broken lines indicating continuous length and repetition of the pattern;

FIG. 2 is a side elevational view of the building;

FIG. 3 is a rear elevational view of the building; and FIG. 4 is a front elevational view of the building.

I claim:

The ornamental design for a building, as shown and described.
